company of France

Application February 24, 1940, Serial No. 320,534
In Luxembourg March 18, 1939

16 Claims. (CL 123—169)

The present invention relates to spark plugs for automobile vehicles.

Two of the chief elements of a spark plug of this kind, to wit the insulating portion and the central electrode, respectively, are usually assembled together by means of a special cement. This method of assembly involves serious drawbacks: Either it is not fluidtight to gases, which are thus allowed to leak out through the plug, or it lacks elasticity, in which case, the insulating portion of the plug may burst under the effect of the expansion of the central electrode.

There is also another way of assembling the insulating portion and the central electrode, which consists in packing the space between the electrode and the walls of the housing provided in said insulating portion for said electrode with a powdery matter such as talcum or crushed steatite, or any other suitable body.

This last mentioned method ensures good results as to the strength and fluidtightness of the assembly, but it is disadvantageous from the point of view of the cooling of the electrode, because the tightly packed matter that is used is a bad conductor of heat and operates as heat insulating means around the electrode.

The object of the present invention is to provide a spark plug which obviates the above mentioned drawbacks, and in particular a method of assembling the insulating portion of a spark plug with its central electrode which permits of obtaining a perfect fluidtight connection irrespective of the variations of temperature to which the plug is subjected on an internal combustion engine, and a better outflow of the heat of the electrode toward the electricity insulating portion.

According to an essential feature of the present invention, the spark plug is made in the following manner:

I interpose, between the central electrode, eventually either above or below an enlarged portion thereof, and the housing provided in the electric insulating sheath for said electrode, a malleable matter which is a good conductor of heat. Advantageously, for this purpose, according to 45 the invention, I deform, by means of a high pressure, a ring constituted of said malleable material, for instance a metal such as copper, aluminium, etc., surrounding the electrode rod.

I place on said rod, adjacent to the ring, a tube made of a paste of talcum or steatite and an agglomerating body, which paste has been previously dried.

I engage on said rod, next to said tube, a ring or washer of a malleable material or metal, and 55

I exert on the whole of the ring, the tube and the washer, a very high axial pressure so as to crush them.

In this way, I obtain a perfectly fluidtight connection between the insulating portion and the central electrode. The crushing of the washer serves to prevent any possibility of inflow of the powdery matter into the punching tool which compresses the whole. Also it fixes the elements in position along the rod, and it permits the outflow of heat from the electrode.

The paste above referred to may advantageously be made of the following composition:

	Per cent
15 Talcum	75
Clay	20
Titanium oxide	5

This composition of matter is caused to pass 20 through a tubular drawing tool to form a tube. This tube is cut into portions and dried before or after this cutting.

Other features of the present invention will 25 result from the following detailed description of some specific embodiments thereof.

A preferred embodiment of the present invention will be hereinafter described with reference to the accompanying drawing given merely by way of example, and in which—

30 Fig. 1 is an axial sectional view of the electric insulating portion of a spark plug in which are engaged the electrode rod and the inner ring made of a malleable metal;

Fig. 2 is a view similar to Fig. 1, showing the 35 same elements after the malleable metal ring has been crushed;

Fig. 3 is a similar view showing the same parts after the steatite tube and the upper ring have been engaged on the electrode rod;

40 Fig. 4 is a similar view showing the parts of the spark plug after the electrode has been finally fitted;

Fig. 5 is a detail view showing in elevation partly in section, a portion of the tube of steatite paste.

In the spark plug illustrated by the drawing, a designates the electric insulating body of the plug and b is the central electrode. The electric insulating body is provided, over its whole height, 50 with a conduit or housing a¹ adapted to accommodate said central electrode. The latter includes a rod b¹ having a part b² of enlarged section resting upon the conical (or curved) bearing or bottom of housing a¹ (Fig. 1).

On the rod b¹ of the electrode, I place a ring

c of a malleable metal, in the manner illustrated by Fig. 1.

This ring c is subjected to the action of a high pressure by means of a tubular punching tool d. This pressure may, for instance, be obtained through the action of the piston of a small air pump acting on the upper end of the above mentioned punching tool d. Ring c is deformed as shown by Fig. 2 and, in this state, it ensures an intimate contact between the portion b² of the electrode rod and the inner wall of housing a¹, provided in the electric insulating body of the spark plug, while producing a fluidtight closure of said housing.

The punching tool d is removed, as shown by Fig. 2. Then, I place on the electrode rod a tube of steatite or talcum e, of the kind shown separately by Fig. 5. The diameter of this tube e is slightly smaller than the diameter of the housing a¹ provided in body a, so as to permit of easily introducing this tube into the insulating body, as shown by Fig. 3. On the top of this tube e, I place a ring or washer f of a malleable matter or metal (Fig. 3).

The whole is then subjected to a very high axial pressure by means of tool d acting on washer f, in a manner similar to that above referred to for the crushing of ring c. This pressure produces the crushing of tube e and of washer or ring f, thus ensuring a perfect contact between the electric insulating body a and the central electrode b, and also an absolute fluidtightness. This state is illustrated by Fig. 4.

The insulating body a obtained as shown by Fig. 4, and having its electrode b satisfactorily fitted therein is then mounted in its metallic cap in the usual manner.

Of course, the tube of matter e is not necessarily made of a single element. It might for instance be made of a plurality of superposed cylindrical elements, which would be subsequently agglomerated together in a perfectly intimate manner by the crushing action performed by tool d or any other means so that in the final state illustrated by Fig. 4 the whole of the matter is tightly packed in a uniform manner around rod b and between the end metal rings c and f.

In a general manner, while I have, in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within the scope of the appended claims.

What I claim is:

1. A method of securing in the shouldered bore of the insulating core of a spark plug a central electrode smaller in cross section than the larger portion of the bore, which comprises inserting said electrode into the bore, engaging on said electrode a ring of malleable, heat-conducting matter, subjecting said ring to a high compression so as to deform it against the shoulder and the side wall of the larger portion of said bore, placing next to said ring at least one tube of agglomerated powdery material, and successively, a washer of malleable, heat-conducting matter, and, strongly compressing the whole in the axial direction so as to deform the elements above mentioned and to apply them tightly against the walls of the electrode and of the larger portion of the bore.

2. A method of securing in the shouldered bore of the insulating core of a spark plug a central electrode smaller in cross section than the larger portion of the bore, which comprises inserting said electrode into the bore, engaging on said electrode a ring of malleable metal, subjecting said ring to a high compression so as to deform it against the shoulder and the side wall of the larger portion of said bore, placing next to said ring at least one tube of agglomerated powdery material, and, successively, a washer of malleable metal, and strongly compressing the whole in the axial direction so as to deform the elements above mentioned and to apply them tightly against the walls of the electrode and of the larger portion of the bore.

3. A method of securing in the shouldered bore of the insulating core of a spark plug a central electrode smaller in cross section than the larger portion of the bore, which comprises inserting said electrode into the bore, engaging on said electrode a ring of malleable metal, subjecting said ring to a high compression so as to deform it against the shoulder and the side wall of the larger portion of said bore, placing next to said ring at least one tube of agglomerated mixture comprising talcum and clay, and, successively, a washer of malleable metal, and strongly compressing the whole in the axial direction so as to deform the elements above mentioned and to apply them tightly against the walls of the electrode and of the larger portion of the bore.

4. A method of securing in the shouldered bore of the insulating core of a spark plug a central electrode smaller in cross section than the larger portion of the bore, which comprises inserting said electrode into the bore, engaging on said electrode a ring of malleable metal, subjecting said ring to a high compression so as to deform it against the shoulder and the side wall of the larger portion of said bore, placing next to said ring at least one tube of agglomerated mixture comprising steatite and clay, and, successively, a washer of malleable metal, and strongly compressing the whole in the axial direction so as to deform the elements above mentioned and to apply them tightly against the walls of the electrode and of the larger portion of the bore.

5. A method of securing in the shouldered bore of the insulating core of a spark plug a central electrode smaller in cross section than the larger portion of the bore and having a ring around it and integral with it, which comprises inserting said electrode into the bore, so that said integral ring rests on the shoulder of said bore, engaging on said electrode a ring of malleable heat-conducting matter, subjecting said malleable ring to a high compression so as to deform it against the ring integral with the electrode and against the shoulder and the side wall of the larger portion of said bore, placing next to said ring at least one tube of agglomerated powdery material, and, successively, a washer of malleable, heat-conducting matter, and strongly compressing the whole in the axial direction so as to deform the elements above mentioned and to apply them tightly against the walls of the electrode and of the larger portion of the bore.

6. A method of securing in the shouldered bore of the insulating core of a spark plug a central electrode smaller in cross section than the larger portion of the bore and having a ring around it and integral with it, which comprises inserting said electrode into the bore, so that said integral ring rests on the shoulder of said bore, engaging

on said electrode a ring of malleable metal, subjecting said malleable ring to a high compression so as to deform it against the ring integral with the electrode and against the shoulder and the side wall of the larger portion of said bore, placing next to said ring at least one tube of agglomerated powdery material, and, successively, a washer of malleable metal, and strongly compressing the whole in the axial direction so as to deform the elements above mentioned and to apply them tightly against the walls of the electrode and of the larger portion of the bore.

7. A method of securing in the shouldered bore of the insulating core of a spark plug a central electrode smaller in cross section than the larger portion of the bore and having a ring around it and integral with it, which comprises inserting said electrode into the bore, so that said integral ring rests on the shoulder of said bore, engaging on said electrode a ring of malleable metal, subjecting said malleable ring to a high compression so as to deform it against the ring integral with the electrode and against the shoulder and the side wall of the larger portion of said bore, placing next to said ring at least one tube of agglomerated mixture comprising talcum and clay, and, successively, a washer of malleable metal, and strongly compressing the whole in the axial direction so as to deform the elements above mentioned and to apply them tightly against the walls of the electrode and of the larger portion of the bore.

8. A method of securing in the shouldered bore of the insulating core of a spark plug a central electrode smaller in cross section than the larger portion of the bore and having a ring around it and integral with it, which comprises inserting said electrode into the bore, so that said integral ring rests on the shoulder of said bore, engaging on said electrode a ring of malleable metal, subjecting said malleable ring to a high compression so as to deform it against the ring integral with the electrode and against the shoulder and the side wall of the larger portion of said bore, placing next to said ring at least one tube of agglomerated mixture comprising steatite and clay, and, successively, a washer of malleable metal, and strongly compressing the whole in the axial direction so as to deform the elements above men-

tioned and to apply them tightly against the walls of the electrode and of the larger portion of the bore.

9. A spark plug comprising an insulating core having a central shouldered bore therethrough, an electrode mounted in said bore, a first ring of malleable, heat-conducting matter surrounding said electrode and tightly applied against it and against the shoulder of the bore, a tubular layer of agglomerated powdery material compressed against said ring between said electrode and the wall of the larger portion of said bore, over a portion of the length of said electrode, and a second ring of malleable, heat-conducting matter tightly applied against said tubular layer, between the electrode and the wall of the bore.

10. A spark plug in accordance with claim 9, and in which said rings are of a malleable metal.

11. A spark plug in accordance with claim 9, and in which said agglomerated powdery material is a mixture comprising talcum and clay.

12. A spark plug in accordance with claim 9, and in which said agglomerated powdery material is a mixture comprising steatite and clay.

13. A spark plug comprising an insulating core having a central shouldered bore therethrough, an electrode mounted in said bore and having a ring around it and integral with it, a first ring of malleable, heat-conducting matter surrounding said electrode and tightly applied against its side wall and said integral ring and against the wall of the bore, a tubular layer of agglomerated powdery material compressed against said ring between said electrode and the wall of the larger portion of said bore, over a portion of the length of said electrode, and a second ring of malleable, heat-conducting matter tightly applied against said tubular layer, between the electrode and the wall of the bore.

14. A spark plug in accordance with claim 13, and in which said rings are of a malleable metal.

15. A spark plug in accordance with claim 13, and in which said agglomerated powdery material is a mixture comprising talcum and clay.

16. A spark plug in accordance with claim 13, and in which said agglomerated powdery material is a mixture comprising steatite and clay.

CHARLES EUGÈNE MEYER.
